By his Attorney Joseph Matlevich
George E. Heinrich

UNITED STATES PATENT OFFICE.

JOSEPH MATLEVICH, OF WASHINGTON PARK, ILLINOIS.

COMBINATION-CABINET.

1,391,487.

Specification of Letters Patent. Patented Sept. 20, 1921.

Application filed February 26, 1921. Serial No. 447,979.

To all whom it may concern:

Be it known that I, JOSEPH MATLEVICH, a citizen of Lithuania, residing at Washington Park, county of St. Clair, and State of Illinois, have invented certain new and useful Improvements in Combination-Cabinets, of which the following is a specification.

This invention relates to improvements in furniture, particularly stands used for supporting and holding various articles of personal wear or toilet articles and the like.

It is the principal object of this invention to provide a simple, efficient and practical article of this kind, part of which may be readily transformed into a writing desk, or when the desk is not in use, it may serve as a back rest for persons using the two seats combined with the stand.

Another object of the invention is the provision of an article of this type which may be readily and conveniently transported from one place to another.

These and other like objects are attained by the novel construction and combination of parts hereinafter described and shown in the accompanying drawings, forming a material part of this disclosure, the single figure of which shows a stand constructed according to the present invention in perspective view.

The base of the stand is made of the front and rear bars 10 provided with feet 11 supported on rollers 12, and connecting side elements 13 connect the feet 11 of the two front and rear bars 10.

Uprights 14, pairwise arranged at the front and rear are connected by rails 15 intermediate their length, and their upper ends support a platform 16.

Upon the upper, flat edges 17 of the side elements 13, the feet 18 of vertical posts 19 are resting, the upper ends of which are connected by a sill or board 20 forming the top and guide of two drawers 21 and 22 provided with handles 23 and 24 and which are slidably guided between the posts 19 and resting on a strip or board 25.

Underneath said strip a roller 26 is held between the posts 19 from which various articles, a towel or the like may be hung. Four pillars or posts 27 are supported on the board 20 and carry upon their upper ends an ornamental cornice 28 on top of which a railing 29 is arranged.

The two rear posts 27 form a support for a mirror 30 in a frame 31.

Above the platform 16 shelves or arm rests 32 are arranged through which the posts 19 pass and braces 33 forming a triangle secured at its apex to the posts 19 support the shelves 32.

Cross strips 34 connect the posts 19 above the platform 16 and a plate 35 is held between the post 19 and can be used as a table in which case it rests upon the shelves 32 while the person or persons intending to use the board 35 as a table, find a seat on platform 16 on both sides of the table. A rack or support 36 secured at the rear of board 20 may be used as a support for the lower edge of a picture frame, which may be hung from the railing 29.

In use, the space within the railing 29 may be used as a holder for newspapers, magazines, or hats and the like while coats or other garments can be hung from the four corner blocks 37 of the railing 29.

The board or shelf 20 may serve as a support for various toilet articles for instance powder boxes, and the drawers 21 and 22 are intended for the storage of comb, brush etc. The plate 35 when supported horizontally upon the rests 32, can be used as a writing desk for persons using the platform 16 as seats to both sides of the table, or the plate 35 may be used to carry various articles as a lamp etc. The rollers 12 will permit an easy transportation of the device from place to place.

Having thus described my invention, what I claim as new and desire to secure by Letters Patent of the United States, is:—

A stand of the character described, comprising a base on rollers, a plurality of vertical standards supported on said base, arm rests on two of said standards, a platform constituting two seats on the other of said standards, a platform constituting a plate normally held between the above mentioned two of the standards to constitute a back rest for persons occupying said seats and adapted to rest in its horizontal position on said arm rests to form a table, and means supported by and between said two standards to form a holder for various articles of personal wear and toilet articles.

In testimony whereof I have affixed my signature.

JOSEPH MATLEVICH.
